UNITED STATES PATENT OFFICE.

FREDERICK MYERS, OF LIVERPOOL, COUNTY OF LANCASTER, ENGLAND.

TYPE-WRITING MACHINE.

SPECIFICATION forming part of Letters Patent No. 441,687, dated December 2, 1890.

Application filed November 29, 1889. Serial No. 331,972. (No model.) Patented in England November 23, 1888, No. 17,041; in Austria-Hungary April 3, 1889, No. 3,468 and No. 12,668; in France May 22, 1889, No. 198,406, and in Belgium May 22, 1889, No. 86,324.

To all whom it may concern:

Be it known that I, FREDERICK MYERS, engineer, a citizen of the United States, residing at Liverpool, in the county of Lancaster, in the Kingdom of England, have invented certain new and useful Improvements in Type-Writing Machines, (for which I have received Letters Patent in England, No. 17,041, dated November 23, 1888; in France, No. 198,406, dated May 22, 1889; in Belgium, No. 86,324, dated May 22, 1889, and in Austria-Hungary, No. 3,468 and No. 12,668, dated April 3, 1889,) of which the following is a specification.

This invention relates to that kind of type-writing machines in which the type are arranged above the paper carriage or platen upon the peripheries of one or more vertical disks, the said disks or each disk (if there be more than one) being rotated into a given position for each type thereon, the relative amounts of such rotation depending upon the relative distances to which the key-levers or mechanism connected therewith are or is depressed. Certain portions of the mechanism are, however, applicable to type-writing machines other than the above.

The machine herein described is in some respects similar to that set forth in my pending applications, Serial Nos. 317,689 and 326,277; and the present invention relates more especially to the adjustment and operation of the platen and its supporting-bed, to the longitudinal adjustment and operation of the type-wheel, to the locking of the type-wheel in its exact position for printing, and to various details of construction.

In the drawings, Figure 1 is a plan of the machine, parts being shown broken away and other parts removed. Fig. 2 is a front elevation with parts in section and other parts removed. Fig. 3 is a sectional elevation similar to Fig. 2, showing the mechanism for operating the platen. Fig. 3^a shows a modification of part of the mechanism depicted in Fig. 3. Fig. 4 is a detached view of a portion of the mechanism shown in Fig. 3. Fig. 5 is an elevation of the right-hand end of the machine, part being in section. Fig. 5^a is a section on line $\alpha\alpha$, Fig. 5. Fig. 6 is a transverse sectional elevation on line yy , Fig. 1.

Fig. 7 is an elevation of the left-hand end of the machine, the key-levers being taken away and the platen and platen-frame removed. Fig. 8 is a front sectional elevation of a modified arrangement of mechanism for locking 55 the type-wheel. Fig. 9 is a side elevation of the mechanism shown in Fig. 8, parts of the framing, &c., being broken away.

A is the main frame of the machine, provided with suitable feet A⁶.

B' is an overhanging standard mounted upon the main frame A, and adapted to support the type-wheel H, &c. The type-wheel H is rigidly secured upon a shaft h, which is capable of both a rotary and longitudinal 65 movement in a manner hereinafter described. The type-wheel is located with its periphery in close proximity to that of the platen R below it. The type are arranged upon the periphery of the type-wheel, preferably in three 70 parallel groups X Y Z, in the same manner and for the same purpose as set forth in my aforesaid application, Serial No. 317,689.

C' C' are the key-levers, which are each provided with a suitable finger-key, and are all arranged and mounted in a movable manner upon a fixed lever-shaft D, substantially as described in my pending application, Serial 75 No. 317,689. All the levers are capable of the same amount of downward travel, their upward movement being limited by a check-rod c² and their downward movement by the rib a⁸ on the main frame, or by the lower ends of the slots in the lever guide-comb C².

c' c', Figs. 6 and 7, are the lever-elevating 85 springs carried by a bridge-piece c⁷, and secured thereto by screws c⁸, Fig. 1.

The type-wheel pinion K is rigidly fixed to the shaft h, and is connected by suitable gearing—such as F² F' F³, Figs. 1, 2, and 5—with 90 the type-wheel-operating frame C⁴, which is pivoted at its rear edge, as at a⁶, to the main frame, and has its front edge lying transversely below the key-levers C'.

c⁵, Figs. 5 and 6, is an elevating-spring for 95 the frame C⁴, the upward movement of which is limited by the contact between the sides of the frame and the shaft D or a collar d² thereon, as seen in Fig. 6.

As set forth in my pending application, Se- 100

rial No. 317,689, the front edge of the frame C⁴ is provided with a series of striking-points formed by a series of adjustable screws c⁶, which have their upper ends located at various 5 distances below the levers C', so that each lever will when fully depressed turn the frame C⁴, and consequently the type-wheel H, into a different definite position, such position being that required to print with the type represented by the depressed key-lever. The spring c⁵ returns the frame C⁴ and the type-wheel H into their normal positions when a depressed key is released.

The rotative platen R, the sliding platen-frame R', the hinged bed S, carrying the same, the word-spacing device G G' G², the spacing-frame P P', and the line-spacing and inking mechanisms (not shown in the drawings) are all substantially the same as were described in 15 my pending applications, Serial Nos. 317,689 and 326,277, aforesaid. The bed S is hinged on the horizontal pivot s⁴ at its end remote from the type-wheel, and its free end is supported normally on a spring s⁶, which also 20 takes the weight of the bed off the printing mechanism when the latter is operated. The said spring is inserted into a tubular projection s⁷ on the bed and rests upon the upper end of a pin s⁸ on the main frame A. The pin s⁸ is 25 also inserted into the projection s⁷, and serves to prevent lateral movement in the bed as it rises and falls in the manner hereinafter explained.

The spacing-frame P P' is pivoted at its 30 rear edge, as at a⁶, to the main frame, and is held normally with its front edge P in contact with the undersides of all the key-levers by means of an elevating-spring P⁴, Fig. 7. The frame is thus depressed at each depression of a key-lever.

The hinged bed S may be raised (at or during the completion of a key-lever's travel) to perform the printing operation by the following mechanism, which is used in conjunction 45 with a modified form of spacing mechanism: The spacing-rack T' is fixed with its teeth downward on the under side of the sliding platen-frame R'. A horizontal shaft V, Figs. 3 and 4, lying below the platen-frame 50 and at right angles to its axis, carries a more or less upright arm or pawl V', whose salient end v is adapted to engage the teeth in the said spacing-rack T'. The horizontal shaft V is connected with a second arm V², Figs. 3 and 55, preferably longer than the first, and lying in an approximately horizontal position. The arm V² is mounted upon a pivot v' above the shaft, as in Fig. 3, and is connected to the shaft by a depending arm v², which forms 60 an angle-lever with the arm V², and is provided at its lower end with a slot v³, adapted to engage a pin on a short depending arm v⁴, carried by the said shaft V, or the arm V² might be cranked downwardly and laterally 65 and attached directly to the shaft V, as in Fig. 3^a. The former arrangement is, however, preferable. The salient outer end of the

horizontal arm V² is engaged by a spring-catch V³, Figs. 1, 3, and 6, which is mounted upon a pin V⁴, moving with the side P' of the 70 spacing-frame, the catch being preferably extended upward and provided with a slot V⁵, through which a fixed guiding-pin V⁶ projects. A spring V⁷ or its equivalent returns the shaft V and arms V², v², v⁴, and V' to 75 their normal positions after each operation, and a suitable buffer or stop (such as the upper end of the slot v⁶, Fig. 3, in the type-wheel standard B') may be provided to limit the upward movement of the arm V² when 80 returned by its spring.

The above-combined arrangement works as follows: The side P' of the spacing-frame on being depressed draws the spring-catch V³ downward, and the latter, by its engagement with the horizontal arm V², turns the shaft V about its axis to such an extent that the upright arm V' thereon, by reason of the engagement of its upper end v with the perpendicular face of a tooth on the spacing-rack T', moves the latter, and consequently 90 the platen, the necessary distance for spacing a character or word. As soon as the platen has been moved into the proper position the spring-catch V³ is disengaged from the horizontal arm V² by means of a suitable device, such as by the contact between the inclined part V⁸ of the said catch and a stationary (and preferably adjustable) abutment V⁹ on the standard B'. The arms V' V² v² v⁴ and 95 the shaft V are now forcibly returned to their normal positions by the spring V⁷, and the salient end of the upright arm V', in sliding over the inclined back t³, Fig. 4, of the adjacent rack-tooth, raises the platen, platen-frame, and hinged bed a distance sufficient to 100 press the paper on the platen against the type. The bed and platen drop into their normal 105 positions as soon as the extremity of the upright arm reaches the face t⁴ of the rack-tooth. 110 Any tendency of the rack and platen to move backward on the return movement of the upright arm V' may be prevented by a check-pawl t² on the platen-frame, which engages a 115 fixed check-rack T on the hinged bed, having its teeth facing in the reverse direction to the teeth on the spacing-rack T'. When it is required to withdraw the platen-frame, the pawl t² is thrown back, and the upright arm V' moves forward till it is clear of the rack-teeth by raising the handle v⁵, attached to the 120 short arm v⁴.

When the printing is performed by means of the above combined arrangement, it is preferable to leave a blank space or gap h' in the 125 groups of type on the lower side of the type-wheel, in order that the platen, when raised in spacing a word, may not come in contact with the inked type. This raising of the platen is due, as in the case of the printing 130 operation hereinbefore described, to the sliding contact which takes place between the inclined back t³ of the rack-tooth and the point of the upright arm V' as the platen-

frame is drawn along by the depression of the spring-raised spacing-key G. The latter is carried by the levers G', mounted on the shaft D, and actuates the rack T' and platen-frame 5 in the same manner as the key-levers C'.

The type-wheel may be moved longitudinally by the following arrangement into any of three given positions, so that each of its three groups of type may, as required, be 10 brought directly over the platen. An operating-lever W' is carried by one end of an oscillatory shaft W, Figs. 1, 2, 5, 6, and 7, mounted upon the main frame A. The other end of the shaft carries an upright arm W², Figs. 1, 2, and 5, the upper forked end of which engages a groove f' on the boss of the counterbalanced toothed quadrant F² aforesaid. The latter is capable of sliding longitudinally upon its shaft F when operated by 15 the lever W', and such longitudinal movement is transmitted to the type-wheel shaft h by reason of the flanges of the pinion K, which gears with the quadrant. 20

The operating-lever may be provided with 25 a spring pin or catch, which enters one of a series of holes or indentations w', Figs. 6 and 7, on the main frame, and serves to lock the lever in any of its three positions corresponding to the three longitudinal positions of the 30 type-wheel; or the lever W' may itself form the spring-catch by being made thin and flexible in a lateral direction, as shown in Fig. 2, and provided with a projecting pin w, adapted to engage the indentations w'. When 35 it is required to adjust the type-wheel into another position, a slight forward or backward pressure on the operating-lever W' is sufficient to cause the pin w to spring out of an indentation w'. The ready adjustment of 40 the type-wheel in its two extreme positions may be assisted by providing the shaft F with a collar f², Figs. 1 and 5, which bears against one end of the quadrant-boss in one extreme position, the opposite end of the boss 45 being adapted in the other extreme position to bear against the pinion F'.

Instead of causing the quadrant F² and pinion F' to slide upon their shaft as one piece, as described in my pending application, Serial 50 No. 326,277, I make the pinion a fixture on the shaft, as by that means I obtain a constant amount of rotation in the pinion (and therefore in the type-wheel) for a given amount of movement in the hinged frame C⁴, which was not the case when the distance of 55 the pinion from the frame-axis a⁶ varied with each longitudinal position of the type-wheel. The rotary movement of the pinion may be imparted to the quadrant by the usual key 60 or feather, or by a pin f³, Figs. 5 and 5^a, which is attached to the pinion and passes into a hole in the quadrant-boss.

The type-wheel may be locked during the operation of printing by the following mechanism: A locking-wheel H⁵ is fixed upon the type-wheel shaft h, and bears on or near its

periphery a series of notches H^{3a} or their equivalent, having the same relative angular position as the type on the type-wheel. A locking bar or pawl L⁶, Figs. 1, 2, and 5, is operated from the spacing-frame P P' in the following manner, and is adapted by the depression of such frame to perform the locking operation in a positive manner prior to the printing operation. The locking-bar L⁶ 70 is pivoted upon the standard B', as at 7, Figs. 2 and 5, and its upper end is provided with a salient edge L, which is located normally in proximity to and is adapted to engage the side of the locking-wheel. The salient end L^{8c} is extended outward toward the front of the machine, as shown in Figs. 1 and 5, so that it may engage the locking-wheel in any of its three longitudinal positions. The lower end of the bar L⁶ is provided with a short horizontal arm L⁷, which carries a projecting pin L⁸. This pin is engaged by the forked end of an arm P⁶, carried by the bar P of the spacing-frame. (See Figs. 2 and 6.) The distance between the two branches of the forked end 85 of the arm is greater than the diameter of the pin L⁸, and the latter rests normally against the edge of the lower branch, as shown in Fig. 2, so that the locking-bar is not actuated until the spacing-frame has been depressed 90 for a certain distance. The bar L⁶ is withdrawn from engagement with the locking-wheel by a spring L⁹, Figs. 2 and 5, which bears against the tail L¹⁰ on the bar and holds the same normally against the side of the 95 standard B'. Each time the spacing-frame is fully depressed the locking-bar L⁶ is moved toward the wheel H⁵, and, as the movements of the spacing-frame, hinged frame C⁴, type-wheel, and locking-bar are all arrested at the 100 same moment by reason of the contact of the key-lever with the guide-plate C², it will be obvious that the parts may be so proportioned that the salient end L will arrest and lock the locking-wheel as soon as the type-wheel is 105 brought into its proper position, which is at about the same moment that the spacing-frame reaches its lowest position. By this locking mechanism there is no possibility when the machine is being operated rapidly 110 of the type-wheel being swung beyond the proper point or of its being arrested too soon by the locking-bar. The locking-bar L⁶ is withdrawn from engagement with the locking-wheel on the return of the spacing-frame 115 by the spring L⁹ aforesaid.

Instead of pivoting the bar L⁶ to the type-wheel standard, it may be mounted, as shown in Figs. 8 and 9, in such a manner as to be capable of being reciprocated in a vertical direction, its upper salient end L being extended forward, as before, and placed directly below the locking-wheel H⁵ at a suitable distance therefrom.

The side P' of the spacing-frame is provided with a downward extension P⁵. This extension carries a pin l³, which engages one

end of a rocking-lever L⁵, mounted upon a fixed pivot A². The opposite end of the lever engages a pin l⁴, carried by the locking-bar L⁶.

t⁵ t⁶ are guides for the pin l⁴ and bar L⁶, respectively. The action of this modified locking arrangement is precisely similar to that described with reference to Figs. 1, 2, and 5.

In describing the foregoing machine and its modifications it has been assumed that the matter was printed from left to right. The machine could, however, with slight modifications be arranged to print from right to left.

I declare that what I claim is—

1. In a type-writing machine, the combination, with a platen, a sliding platen-frame, a platen-frame-supporting bed hinged at one end, as described, a series of keys, and spacing mechanism operated at each depression of a key, of a spacing-rack movable synchronously with said platen-frame and having downwardly-facing teeth with inclined backs, as described, a vibratory spacing-pawl located near the free end of the hinged bed and having a salient end adapted at each successive operation of said spacing mechanism to engage the face of the adjacent rack-tooth and move the platen the required distance, means for automatically releasing said pawl from the control of the depressed key on the completion of the spacing operation, and a device for quickly returning the salient end of the pawl over the inclined back of the succeeding tooth, whereby the spacing and printing operations are successively performed before the release of the key, substantially as described.

2. In a type-writing machine, the combination, with a platen R, sliding platen-frame R', and supporting-bed S, hinged at one end, as described, of a spacing-rack T', fixed to the bottom of the frame R' and having on its under side a series of teeth with inclined backs t³ and approximately perpendicular faces t⁴, a vibratory pawl V', located below said rack and having its salient upper end v adapted at each successive forward stroke of the pawl to engage the perpendicular face of the adjacent rack-tooth, spacing mechanism whereby the said pawl is moved forward the required distance at each depression of a key, and means for quickly returning the salient end of the pawl over the inclined back of the succeeding tooth prior to the release of the key, substantially as described.

3. In a type-writing machine, the combination, with the platen R, sliding platen-frame R', and hinged bed S, of a spacing-rack movable synchronously with the frame R' and having on its under side a series of teeth with inclined backs, as described, a vibratory spacing-pawl located below said rack at a suitable distance from the hinge-axis of the bed and having its salient end adapted at each successive forward stroke of the pawl to engage the face of the adjacent rack-tooth, spacing mechanism whereby the said pawl is moved forward the

required distance at each depression of a key, a spring-catch device forming an element of said mechanism, means adapted to automatically disconnect said device on the completion of the spacing operation, and a device for quickly returning the salient end of the pawl over the inclined back of the succeeding rack-tooth on the disconnection of said spring-catch, substantially as described.

4. In a type-writing machine, the combination, with the platen R, sliding platen-frame R', and hinged bed S, of a spacing-rack T', movable synchronously with the frame R' and having on its underside a series of teeth with inclined backs, as described, a vibratory spacing-pawl located below said rack, as described, and adapted at each successive forward stroke to engage the face of the adjacent rack-tooth with its salient end, a spacing-frame P P', adapted to be depressed at each depression of a key, a spring-catch V³, mounted on said frame, a horizontal arm V², connected with the spacing-pawl and having its outer end engaged by said catch and adapted to be moved downward thereby to effect the forward movement of the pawl, an inclined piece V⁸ on said spring-catch, an abutment V⁹, bearing against the piece V⁸ and adapted to thrust the catch off the arm V² at the termination of its downward stroke, and a spring V⁷, adapted to return both arm and pawl to their normal positions on the release of the catch, substantially as described.

5. In a type-writing machine, the combination, with the platen R, platen-frame R', and hinged bed S, of a spacing-rack T', fixed on the under side of said frame and having teeth t³ t⁴, as described, an oscillatory spacing-pawl B', adapted to engage said teeth, as described, with its salient end, a shaft V, carrying said pawl, a depending arm v⁴, fixed on said shaft, a depending arm v², mounted on a pivot above the shaft V and having a slot v³ engaging a pin in the lower end of arm v⁴, a spring-elevated horizontal arm V², movable with said arm v⁴, a spring-catch V³, engaging said arm V² in a direction opposite to the tension of its spring, a spacing-frame carrying said catch and adapted to be depressed at each depression of a key, and means for automatically disengaging said catch from the arm V² on the completion of the spacing operation, substantially as described.

6. In a type-writing machine, the combination of the platen R, platen-frame R', hinged bed S, spacing-rack T', pawl V', shaft V, arms v⁴ v² V², spring-catch V³, spacing-frame P P', catch-guiding device V⁵ V⁶, inclined thrust-piece V⁸, adjustable abutment V⁹, and returning-spring V⁷, all arranged and combined substantially as described and shown.

7. In a type-writing machine, the platen R, sliding platen-frame R', hinged bed S, spacing-rack T', fixed to said frame and having teeth on its under side with inclined backs, as described, vibratory spacing-pawl V', adapted at each

forward stroke to engage the face of one of said teeth and move the rack and platen-frame forward a tooth-space and adapted at each return-stroke to slide over the inclined back 5 of the following tooth and raise the platen-frame and bed, as described, in combination with a check-rack T, fixed to said bed S and having teeth of a corresponding pitch to those of rack T', and a check-pawl t^2 , mounted on 10 the frame R' and adapted to engage the teeth of said rack T in a reverse direction to the engagement of the rack T', and pawl V', whereby any tendency of the platen-frame to move backward during the return-stroke of 15 the pawl V' is prevented, substantially as described.

8. In a type-writer, the sliding platen-frame R', the rack T' thereon, the vibratory pawl V', engaging the same, the arms $v^4 v^2 V^2$, arranged substantially as described and movable synchronously with said pawl, the spring-catch V^3 , mounted on the compressible spacing-frame and adapted to engage the upper side of said arm V^2 , in combination with 25 a handle v^5 , movable with the pawl V', whereby the latter may be moved forward to an abnormal extent and disengaged from its rack when the platen-frame is to be withdrawn, substantially as described.

30 9. In a type-writer, the combination of a series of compressible key-levers, a spacing-frame P P', adapted to be depressed thereby, a link V^8 , connected at its lower end to the said spacing-frame, an angle-lever $V^2 v^3$, having its lateral arm V^2 connected to the upper end of said link, a depending arm v^4 , fixed to a shaft V and engaged, as described, by the depending arm v^2 of the angle-lever, an upright spacing-pawl V', also fixed to said shaft 35 V, and a spacing-rack T', fixed to the sliding platen-frame and having teeth on its under side adapted to be engaged by said pawl at each forward stroke thereof, whereby the spacing operation is accomplished at each 40 depression of a key-lever, substantially as described.

45 10. In a type-writer, a type-wheel H, a platen R, located at a suitable distance below said wheel, a sliding platen-frame R'; and a 50 frame-supporting bed S, hinged at its end remote from the type-wheel, in combination with a spacing-rack T', fixed to said frame R' and having teeth with inclined backs facing downward, as described, and an upright 55 spacing-pawl V', capable of a to-and-fro movement in a fixed path approximately parallel to the movement of the rack and adapted at each return-stroke to engage the inclined back of the adjacent rack-tooth, whereby the hinged 60 platen-supporting bed is raised the necessary distance to produce an impression, substantially as described.

65 11. In a type-writer, the combination, with the compressible spacing-frame P P', the platen-frame R', the spacing-rack T' on said frame R', and the vibratory spacing-pawl V',

adapted to engage said rack, as described, of an arm V^2 , movable synchronously with said pawl, as described, a spring-catch V^3 , movable synchronously with the spacing-frame 70 and adapted to engage said arm on the downward movement of the frame, an inclined thrust-piece V^8 on the said spring-catch, and an abutment V^9 , adapted to engage said piece V^8 and thrust the catch outward, whereby the 75 spacing-frame and spacing-pawl are disconnected at the proper moment, substantially as and for the purpose described.

12. In a type-writer, the combination of the sliding type-wheel H, flanged type-wheel pinion K, sliding segment F^2 , gearing therewith, oscillatory arm W^2 , having a forked end engaging a groove in the segment-boss, oscillatory shaft W, carrying said arm, laterally-flexible operating-lever W' , fixed on said 85 shaft, lateral pin w on said lever, and a stationary piece on the machine-frame provided with indentations w' , having the same number and relative positions as the groups of type aforesaid and each adapted to receive 90 the outer end of said pin, substantially as described.

13. In a type-writer, the combination of the hinged type-wheel-operating frame C^4 , the vertical rack F^8 thereon, the rack-pinion 95 F' , mounted loosely upon a shaft F at a fixed distance from the frame-axis, the type-wheel, the toothed type-wheel-operating quadrant F^2 , also mounted loosely on the shaft F and capable of a longitudinal movement thereon 100 to and from said axis synchronously with the longitudinal movement of the type-wheel, and a device f^3 , adapted to transfer the oscillatory motion of the pinion F' to the segment F^2 , substantially as and for the purpose described. 105

14. In a type-writer, the combination of the type-wheel H, the locking-wheel H^5 , the spacing-frame P P', the locking-bar L^6 , pivoted at its lower end at l^7 and having its upper salient end located in proximity to said locking-wheel, the depending tail L^{10} on said bar, the spring L^8 , adapted to press upon said tail, as described, the lateral arm L^7 on the lower end of the bar, the pin L^8 on said 115 arm, and the forked arm P^6 on the said spacing-frame located normally with the lower branch of its fork in contact with the lower side of said pin and having the upper branch of its fork located normally above the pin 120 and adapted to engage the same during the terminal portion of the downward movement of the said frame, substantially as described.

In testimony whereof I have signed my name to this specification in the presence of 125 subscribing witnesses.
